UNITED STATES PATENT OFFICE.

JERRY S. GREEN, OF LE CLAIRE, IOWA.

SELF-LOCKING CLOTHESLINE RECEIVER.

Application filed December 15, 1926. Serial No. 154,993.

This invention aims to provide novel means for holding a clothes line securely but releasably on a prop.

Figure 1 is a front elevation;

5 Figure 2 is a side elevation;

Figure 3 is a longitudinal section; and

Figure 4 is a cross section.

A metal plate 2 is secured by screws 22 to a prop 1 and is made up of side strips 3 between which is located a guideway 4, off-set keepers 5 connecting the strips 3 at their upper and lower ends, and the strips being supplied at points intermediate their ends with upstanding fingers 6. A metal slide plate 7 is mounted to reciprocate in the guideway 4 of the member 2, beneath the keepers 5, and has an off-set upstanding line seat 8 which is located between the fingers 6 when a rectangularly disposed stop 10 at 10 the upper end of the slide plate 7 rests on the upper end of the prop 1. The slide plate 7 has a depending upper line retainer 9 which projects toward the upper end of the seat 8, there being a reduced slot 11 between the 15 lower end of the retainer 9 and the upper end of the seat 8. The seat 8 is shorter than the fingers 6, and the retainer 9 extends downwardly below a line A—B connecting the ends of the fingers 6, when the stop 10 20 engages the upper end of the prop 1.

The slide 7 is pulled up until the slot 11 is above the line A—B, and the clothes line 12 is engaged in the seat 8, through the slot 11. The slide 7 is released and moves downwardly until the stop 10 engages the upper end of the prop 1, the line 12 being received behind the finger 6, and the general construction being such, as shown in Figure 1, that the line cannot well escape from behind the 25 fingers 6, and out of the seat 8. Stop 10 causes practically all of the weight of the line 12 and the clothes thereon to be car-

ried directly by the prop 1 and not by the securing elements 22 that connect the frame or plate 2 with the prop 1.

45

I claim:—

1. In a device of the class described, a prop, a plate, means for mounting the plate slidably for upward and downward movements on the prop, means for limiting the 50 downward movement of the plate, the plate having an upstanding seat and a depending retainer cooperating with the seat to form a line-receiving slot, and there being an upstanding finger carried by the prop and located at one end of the seat when the plate is in its operative position.

2. In a device of the class described, a prop, a slide mounted to reciprocate on the prop and having a stop adapted to engage 60 the upper end of the prop, there being upstanding fingers on the prop located on opposite sides of the slide, the slide having a depending retainer extended downwardly below a line joining the upper ends of the 65 fingers when the slide is in its operative position.

3. In a device of the class described, a member comprising side strips connected at their ends by keepers, a slide mounted for 70 upward and downward movements between the strips and behind the keepers, the slide being supplied at its upper end with a rearwardly projecting stop, upstanding fingers on the strips, an upstanding seat on the slide, 75 the seat being located between the fingers, and a depending retainer on the slide, the retainer having its lower end spaced from the upper end of the seat to form a line-receiving slot.

80

In testimony that I claim the foregoing as my own, I have hereto affixed my signature.

JERRY S. GREEN.
